Inventor:

Ray Lee Tipton

UNITED STATES PATENT OFFICE.

RAY LEE TIPTON, OF CHICAGO, ILLINOIS.

SAFETY RAZOR.

Application filed July 12, 1927. Serial No. 205,133.

This invention relates to cutlery and more particularly to a razor of the type known as a safety razor.

One object of the invention is to provide a safety razor which is compact and may be stored in a casing resembling a fountain pen and serving as a handle for the razor when its cap is removed.

Another object of the invention is to allow the guard of the razor to be turned from an operative position transversely of its shank to a folded position longitudinally thereof in order to allow the cap to be fitted upon the casing or handle in enclosing relation to the guard and a portion of the shank extending from the casing.

Another object of the invention is to provide the guard with jaws which may serve to retain the guard in its folded position and also serve to engage a blade and secure the blade in engagement with the guard longitudinally thereof with its sharpened edge portion projecting transversely from the shank when it is desired to strop the blade.

Another object of the invention is to provide improved means to retain the blade in engagement with the guard in an operative position.

Another object of the invention is to allow the blade-securing strip to be sprung away from the shank so that an extended end portion of the strip may bear against the rear edge of a blade and urge the blade forwardly so that its sharp edge will bear against abutments at the end of a toothed forward edge of the guard.

Another object of the invention is to provide a guard formed from a single strip of sheet metal bent and folded to assume the desired shape.

Another object of the invention is to allow the rear end portions of the shank and blade-securing strip to frictionally engage the walls of the tubular casing so as to releasably retain the same in the casing and in addition allow the rear end portions of the shank and strip to be employed as a pair of tweezers.

The invention is illustrated in the accompanying drawing, wherein—

Figure 1 is a view showing the razor as it appears when the cap is applied to the casing;

Fig. 2 is a longitudinal sectional view through the razor with the cap in place;

Fig. 3 is a side elevation showing the razor ready for use, and

Fig. 4 is a view showing a blade secured in position to be stropped, the casing being in longitudinal section and the remainder of the razor in elevation.

The casing 1, which constitutes a handle for the razor, is of an elongated tubular construction and resembles the barrel of a fountain pen or a casing of the type in which medical thermometers are stored. The cap 2 which resembles the cap of a fountain pen is removably received upon the open forward end portion of the casing 1 and is preferably provided with a clip 3 so that the device may be secured in a pocket. It will also be obvious that, if desired, a razor blade placed in a protecting jacket may be engaged between the cap and the clip.

The guard, which is indicated in general by the numeral 4, is formed of metal and is provided with a lip 5 from the rear edge of which extends a depending flange 6. The forward edge portion of the lip is serrated to provide teeth 7 and at its ends carries upstanding lugs 8 for engagement by the cutting edge of a blade 9 when the blade is disposed in the operative position shown in Fig. 3. Tongues extend from the rear edge of the lip adjacent the ends thereof and are bent downwardly to provide jaws 10 which are spaced somewhat from the rear face of the flange 6, as shown in Figs. 2 and 3.

The shank 11 of the razor consists of a strip of resilient metal, the forward end of which is pivotally secured against the rear face of the flange 6 by a rivet or other suitable fastener 12 intermediate the clamps 10 so that the guard may be swung from an operative position transversely of the shank to a folded position longitudinally thereof in which position one of the clamps 10 will extend across the shank. A strip 13 which is also of resilient metal extends longitudinally of the shank and is pivotally connected therewith by a rivet or other suitable fastener 14. This strip 13 projects forwardly beyond the outer or forward end of the shank and at its free end carries a lug 15 having a notch 16 formed therein to receive the rear edge of the blade 9 when the blade is disposed in its operative position against the guard. Normally the strip 13 extends close to the shank but when the guard is disposed in its operative position transversely of the shank the blade-securing strip may be sprung away from the shank so that, when the blade is placed against the upper face of the lip 5 of the guard with

its sharpened edge extending along the toothed forward edge of the lip in engagement with the lugs 8, the rear edge of the blade may be received in the notch or seat 16 5 and the resilient strip apply pressure which will urge the blade forwardly and firmly retain it in proper engagement with the guard. After a shaving operation has been completed, it is merely necessary to grasp the blade at 10 its ends between the thumb and forefinger of one hand and the resilient strip may be moved away from the blade so that the blade will be released and may be lifted from the guard. When the blade is removed, the 15 spring strip will return to its initial position shown in Fig. 2 and the guard may then be swung to its folded position in which it extends longitudinally of the shank with one of its clamps extending across the spring 20 strip. This will cause the guard to remain in the folded position. It will also be seen that the blade may be disposed beneath the clamp which overlies the resilient strip with its sharpened edge portion projecting trans- 25 versely from the shank, as shown in Fig. 4, in which position the blade may be stropped in the usual manner. The portions 17 and 18 of the shank and resilient strip between the fastener 14 and their rear ends are bowed 30 away from each other, as shown in Fig. 2, thereby providing cooperating arms which will be pressed toward each other when the casing is thrust upon them and since they will then have a tendency to move apart they 35 will frictionally grip the walls of the casing and retain the casing in its proper position but permit the casing to be removed when so desired. When in place, the casing will constitute a handle for the razor, by means of 40 which it may be easily grasped when shaving or stropping a blade. It should be noted that, when the handle or casing is removed, the rear end portions of the shank and companion strip may be employed as a pair of 45 tweezers and also that the metal from which the shank and strip are formed may be roughened and constitute nail files. By turning the strip or shank about the rivet, they may be caused to extend transversely of each 50 other and the rear end of either strip employed as a nail cleaner. It will thus be seen that the device may be used as a razor and also to care for the nails. When the guard is disposed longitudinally of the shank, the 55 cap may be replaced and the device then easily carried in a pocket. When so carried, the blade may be engaged beneath the clip 3 or placed in a pocket book.

Having thus described the invention, I 60 claim:

1. A safety razor comprising a guard having a toothed edge and abutments at the ends of the guard, a shank extending from said guard, and a resilient strip carried by said 65 shank and extending longitudinally thereof

in contacting engagement therewith and having an end portion extending beyond the shank and projecting from the guard intermediate the width thereof and provided with a lug to engage the back edge of a blade and 70 press the blade firmly against the guard with the cutting edge of the blade extending along the toothed edge of the guard and portions of the blade bearing against the abutments at the ends thereof. 75

2. A safety razor comprising a guard having a toothed edge and abutments at the ends of the guard, a shank extending from said guard, and a resilient strip carried by said shank and extending longitudinally thereof with an end portion extending beyond the shank and projecting from the guard intermediate the width thereof and provided with a lug at its free end, said strip being normally disposed adjacent the guard and adapted to be sprung transversely away from the guard and engage the rear edge of a blade to urge the blade forwardly and hold the blade in engagement with the guard with the cutting edge of the blade extending along the toothed edge of the guard and portions of the blade bearing against the abutments thereof. 80 85 90

3. A safety razor comprising a guard having front and rear edges, abutments adjacent the ends of the front edge, a flange depending from the rear edge of the guard, a shank pivoted to said flange intermediate the ends thereof whereby the guard may be swung from an operative position transversely of the shank to a folded position longitudinally thereof, and a spring strip carried by said shank and having an end portion projecting therefrom and adjacent its outer end provided with means to engage the rear edge of a blade when the guard is disposed transversely of the shank and urge the blade forwardly to dispose its sharpened edge along the forward edge of the guard with its end portions bearing against said abutments. 95 100 105

4. A safety razor comprising a guard having front and rear edges, abutments adjacent the ends of the front edge, a flange depending from the rear edge of the guard, a shank pivoted to said flange intermediate the ends thereof whereby the guard may be swung from an operative position transversely of the shank to a folded position longitudinally thereof, a strip extending longitudinally of said shank with its forward end portion projecting therefrom and adapted to engage the rear edge of a blade and retain the blade in engagement with the guard with the cutting edge of the blade bearing against said abutments, said shank and strip being formed of resilient material and having bowed portions 110 curved away from each other, a tubular handle, said shank and strip being received in said handle with their bowed portions frictionally gripping the walls thereof and their forward end portions projecting therefrom, 115 120 125 130

and a cap adapted to be disposed about the guard and outer end portions of the shank and strip and engaged with said handle.

5. A safety razor comprising a guard, a shank pivoted to the guard intermediate the width thereof whereby the guard may be turned from an operative position transversely of the shank to a folded position longitudinally thereof, a strip carried by said shank and extending longitudinally thereof with its forward end portion projecting from the shank and adapted to retain a blade in engagement with the guard when the guard is disposed transversely of the shank, said shank and strip being resilient and having their rear portions bowed away from each other, a hollow handle fitted upon the shank and strip and held thereon by their bowed portions frictionally engaging the handle, and a cap adapted to be disposed about the guard when folded and engaged with the handle.
6. A safety razor comprising a guard, a shank pivoted to the guard intermediate the width thereof whereby the guard may be turned from an operative position transversely of the shank to a folded position longitudinally thereof, a strip extending longitudinally of the shank at one side thereof and having its outer end portion projecting from the shank and adapted to engage a blade and hold the blade in engagement with the guard when the guard is in an operative position, a fastener passed through the strip and shank intermediate the ends of the strip, the strip and shank being resilient and having their portions between the fastener and their rear ends bowed away from each other, an elongated hollow handle fitted upon said shank and strip with their forward end portions projecting therefrom and held thereon

by their bowed portions frictionally engaging the handle, and a cap adapted to be disposed about the guard when folded and engaged with the handle.

7. A safety razor comprising a guard, a shank pivoted to said guard intermediate its width whereby the guard may be swung from an operative position transversely of the shank to a folded position longitudinally thereof with a portion overlapping the shank, a resilient strip carried by said shank and having its forward end portion projecting from the shank to engage a blade and releasably retain the blade in operative engagement with the guard, and tongues extending from the end portions of the guard and adapted to extend across the shank and strip and engage a blade to hold the blade disposed longitudinally of the shank with its sharpened edge portion projecting from one side thereof whereby the blade may be stropped.

8. A safety razor comprising a guard formed from a sheet of metal having spaced tongues and folded upon itself in spaced relation to the inner ends of the tongues to provide upper and lower leaves and notched along its fold to form teeth, portions of the upper leaf being curved and bent upwardly to provide abutment lugs, the lower leaf being bent in spaced relation to the teeth to provide a depending flange and the tongues being bent to provide jaws spaced from the flange adjacent the ends thereof, a shank pivoted to said flange between the jaws, and a resilient strip carried by and extending longitudinally of the shank with its outer end portion projecting therefrom to engage a blade and hold the blade against the guard with its cutting edge bearing against said lugs.
